UNITED STATES PATENT OFFICE.

THORVALD J. PETERSEN, OF NEW YORK, N. Y., ASSIGNOR TO THE GLOBE LIGHTING FIXTURE MFG. CO., OF BROOKLYN, NEW YORK, A COPARTNERSHIP.

DESIGN FOR A CHANDELIER.

Application filed February 4, 1928. Serial No. 25,175. Term of patent 3½ years.

To all whom it may concern:

Be it known that I, THORVALD J. PETERSEN, a citizen of the United States, residing at New York, in the county of New York and State of New York, have invented a new, original, and ornamental Design for a Chandelier, of which the following is a specification, reference being had to the accompanying drawing, forming part thereof, in which the figure is a view, in perspective, showing my new design.

I claim:

The ornamental design for a chandelier, as shown.

THORVALD J. PETERSEN.
